SELF-SERVICE RESTAURANT BUILDING

Earl S. Swensson, Nashville, Tenn., assignor to Minnie
Pearl's Chicken System, Inc., Nashville, Tenn., a cor-
poration of Tennessee

Filed Apr. 22, 1968, Ser. No. 11,541

Term of patent 14 years

Int. Cl. D25—04

U.S. Cl. D13—1

Fig. 1

Fig. 2

Fig. 3

FIG. 1 is a front elevational view of a self-service restaurant building, showing my design;

FIG. 2 is a side elevational view thereof, viewed from the left side of FIG. 1; and

FIG. 3 is a top plan view thereof, on a reduced scale. I claim:

The ornamental design for a self-service restaurant building, as shown.
